UNITED STATES PATENT OFFICE.

HERBERT H. HEWITT, OF BUFFALO, NEW YORK.

CAR-TRUCK.

1,180,717.

Specification of Letters Patent.

Patented Apr. 25, 1916.

Application filed November 25, 1913. Serial No. 802,871.

To all whom it may concern:

Be it known that I, HERBERT H. HEWITT, a citizen of the United States, and resident of Buffalo, in the county of Erie and State of New York, have invented certain new and useful Improvements in Car-Trucks, of which the following is a full, clear, and exact description.

The present invention relates to car trucks and more particularly to car trucks in which the construction permits the rocking movement of the side frames and wheel axles so that the wheels may rise and fall independently in passing over irregularities in the track without transmitting shocks and strains to the parts of the truck and the car body carried thereby.

The present invention seeks to provide an improved construction for mounting the boxes in the supports or side frames and which will permit the rocking movement of the journal boxes and wheel axles while the journal bearings are properly maintained in line with the car axles and journals.

The invention consists in the features of construction hereinafter set forth, illustrated in the preferred form in the accompanying drawings and more particularly pointed out in the appended claims.

In the drawings, Figure 1 is a plan view of a half-portion of the truck with part of the side frame shown in horizontal section. Fig. 2 is a view partly in elevation and partly in vertical section through the side frame and the journal box mounted thereon. Figs. 3 and 4 are vertical sections taken respectively on the lines 3--3 and 4--4 of Fig. 2.

The side frames of the truck are preferably provided with large central bearings by which they are swiveled to the transverse connecting member of the truck so that the side frames may rock independently in vertical planes. Each side frame is preferably diamond-shape in outline and comprises an enlarged central portion 10, opposite pairs of inclined, converging side arms which extend from the upper and lower parts of the enlarged central portion and which are connected at their outer ends by vertical flanges 12. These parts are preferably formed of integral casting and comprise a central web having wide outer marginal flanges 13 and narrow inner marginal flanges 14, which flanges merge into the end

flanges 12. The central portion of the side frame is provided with a transverse circular opening having an edge flange which, like the flanges 13 and 14, projects in opposite directions from the central web of the side frame and which forms an enlarged, transverse, cylindrical bearing 15. The cylindrical bearing flange is preferably connected, as shown, to the edge flanges 14 by bracing flanges 16.

The transverse connecting means between the side frames is provided with cylindrical end journals or trunnions 17, which fit within the cylindrical bearings 15. On opposite sides of the latter, the side frame is provided with enlarged bosses 18 having pockets therein for receiving keys 19, and which keys extend within slots 20 in the sides of the hollow journal or trunnion 17. The keys are detachably held in place by pins or bolts 21 to thereby detachably secure the side frames to the end transverse connecting means or member of the truck. The slots 20 are wider than the keys so that the side frames are free to rock to a limited extent upon the trunnions or journals 17. In the construction shown, the journals 17 are formed upon the ends of a truck transom 22. The body of the transom is chambered and carries a bolster 23 upon springs 24, the bolster being provided with the usual center and side bearings 25 and 26.

The wheel axles 27 are provided with wheels 28 and projecting end journals 29, which are arranged within the journal boxes 30. The general construction of the journal box is similar to the standard prescribed by the Master Car Builders' Association. Each box is preferably formed of an integral body of metal and is provided with a suitable bearing or brass 31 which rests upon the car axle journal 30. In the present construction, the upper portion of the box is thickened and is provided with a seat for the brass 31 and with a recess at the inner end of the seat for receiving the upstanding flange 32 at the inner end of the brass. The box is mounted to rock in a transverse vertical plane so that the journal bearing or brass can be inserted or removed without employing the usual key.

To permit the rocking movement of the journal box, it is provided with a rounded or curved bearing surface and a suitable support or truck member is provided with

a correspondingly shaped seat for the bearing surface.

In the construction shown, each journal box is arranged within an opening of the side frame which is formed between upper and lower end extensions 33 and 34 that project from each end of the side frame and which are preferably integral therewith. The upper and lower walls of the journal box are provided with convex, concentric bearing surfaces 35 and the extensions 33 and 34 of the side frames are provided with correspondingly shaped seats 36 which engage the bearing surfaces of the box. In the preferred embodiment of the invention set forth, the bearing surfaces 35 and seats 36 are cylindrical and have a common horizontal axis extending lengthwise of the side frame and at right angles to the axis of the journal box. Preferably, also, the axis of the cylindrical bearing surfaces 35 and 36 is arranged closely adjacent or substantially in the same plane with the axis of the box. By the term "axis of the box", as used herein and in certain of the claims, is meant a line that coincides with the axis of the corresponding wheel axle and of the cylindrical bearing surfaces arranged within the box. This construction permits the rocking movement of the journal box and wheel axle in passing over irregularities in the track and also permits the insertion of the journal box between the upper and lower extensions 33 and 34 of the side frame and the removal of the same therefrom in a horizontal direction extending lengthwise of the side frame.

Suitable means are provided for removably holding the boxes in position which will not interfere with the transverse rocking movement of the box. In the construction shown, the upper and lower extensions 33 and 34 of the side frame are provided with aligned openings, and bolts 37 extend through these openings and on opposite sides of the box. The latter is provided on each side with upper and lower lugs 38 having openings or slots 39 therein through which the bolts 37 pass. These slots or openings are transversely elongated so that, while the box is securely held in position, it is free to rock transversely with respect to the side frame. To strengthen the end extensions 33 and 34 of the side frame, an upright 40 is preferably arranged between the outer ends thereof. This upright has inwardly projecting flanges 41 at its upper and lower ends which are arranged within seats in the inner faces of the extensions 33 and 34 and which are perforated to engage the outer fastening bolt 37. By removing the fastening bolts 37 and upright 40, the box may be readily removed for repairs or the like by a movement in horizontal, longitudinal direction, without elevating the

side frame. If necessary in case of accident, a standard M. C. B. box may be rigidly secured in position between the extensions 33 and 34 of the side frame by means of the bolts 37.

The construction, while strong, permits the rocking movement of the journal box and wheel axles in transverse vertical planes without distorting or straining the parts of the truck. The bearings of the journal boxes are thus always maintained in proper alignment with the car axle journals in spite of the rocking movement of the wheel axles as the truck passes over irregularities in the track. Moreover, since the wheel axles are free to rock transversely and the side frames are free to rock independently in longitudinal planes, all of the wheels of the truck will rest solidly on the track in passing over irregularities therein and shocks and strains due to such irregularities will be greatly diminished.

It should be noted that the cylindrical bearing surfaces on the upper and lower faces of the box are wider than the bearing seats 36 on the parts of the side frame and the latter are cut away at their edges as indicated in Fig. 3 so that ample clearance is provided to permit the free rocking movement of the box in a transverse vertical plane. To strengthen the end extensions 33 and 34 of the side frame, they are preferably channel-shape, as shown, being provided with edge flanges 42 which merge into the marginal flanges 13 of the side frame.

The manner of mounting the journal boxes is particularly advantageous in a truck in which the side frames are swiveled for independent rocking movement, but this improved construction can be employed to advantage in trucks of other types.

It is obvious that numerous changes may be made in the details set forth without departure from the essentials of the invention as defined in the claims.

I claim as my invention:

1. In a car truck, a journal box of the Master Car Builders' type having convex, concentric upper and lower bearing surfaces, and a member having correspondingly shaped concave seats for said bearing surfaces and permitting the transverse rocking movement of said box relatively to said member.

2. In a car truck, the combination with a side frame, having upper and lower end extensions, a journal box arranged between said end extension and having a rounded upper bearing surface, said upper end extension having a correspondingly shaped seat for said bearing surface, and removable retaining means connected to said end extensions for holding said box in position; said retaining means being arranged to permit the transverse rocking movement of said

- journal box and its removal from position by a movement lengthwise of said side frame.
3. In a car truck, a side frame having an opening therein, and a journal box arranged in said opening and having convex, concentric upper and lower bearing surfaces, the upper and lower walls of said opening having correspondingly shaped concave seats for said bearing surfaces, and devices for retaining said box in position arranged to permit the transverse rocking movement of said box.
4. In a car truck, a side frame having upper and lower end extensions, journal boxes arranged between said extensions and having upper and lower, cylindrical, convex, bearing surfaces, said extensions having correspondingly shaped concave seats for said bearing surfaces, and uprights removably secured between the ends of said extensions for removably securing said boxes in position.
5. In a car truck, the combination with a side frame, having an opening therein provided with top and bottom side walls, a journal box arranged in said opening and having an upper cylindrical bearing surface, the axis of which is transverse to the axis of the box, the upper side wall of said box having a correspondingly shaped seat for said bearing surface, whereby the box is free to rock in a transverse vertical plane, the side wall of said opening at one end of said bearing surface and said seat being removable to permit the removal of said box by movement parallel to the axis of said cylindrical bearing surface.
6. In a car truck, a side frame having upper and lower end extensions, journal boxes arranged between said extensions and provided with convex, cylindrical bearing surfaces having a common axis at right angles to the axis of the boxes, said extensions having correspondingly shaped seats for engaging said extensions, and a removable upright between the ends of said extensions.
7. In a car truck, a side frame having upper and lower end extensions, journal boxes arranged between said extensions and provided with convex, cylindrical bearing surfaces having a common axis at right angles to the axis of the boxes, said extensions having correspondingly shaped seats for engaging said extensions, and retaining bolts passing through said extensions for removably holding said boxes in position.
8. In a car truck, a side frame having upper and lower end extensions, journal boxes arranged between said extensions and provided with convex, cylindrical bearing surfaces having a common axis at right angles to the axis of the boxes, said extensions
- having correspondingly shaped seats for engaging said extensions, and retaining bolts passing through said extensions for removably holding said boxes in position, the latter having transversely slotted lugs through which said bolts extend.
9. In a car truck, a transverse member, side frames pivotally mounted on the ends of said member to rock independently in vertical planes, said frames having openings at their ends, journal boxes arranged in said openings and having upper, cylindrical bearing surfaces, said side frames having parts provided with correspondingly shaped seats for said bearing surfaces and detachable means for retaining said boxes in position arranged to permit the transverse rocking movement of said boxes and the removal thereof in longitudinal direction.
10. In a car truck, a transverse member, side frames pivotally mounted on the ends of said member to rock independently in vertical planes, said frames having openings at their ends having upper and lower convex, concentric bearing surfaces, the upper and lower walls of said openings having correspondingly shaped concave seats for said bearing surfaces, and means for removably retaining said boxes in position arranged to permit the transverse rocking movement thereof.
11. In a car truck, a side frame having upper and lower end extensions, journal boxes arranged between said extensions, said parts having coöperating bearing surfaces, and retaining bolts passing through said extensions for removably holding said boxes in position, said parts being arranged to permit the rocking movement of boxes in transverse vertical planes.
12. A side frame for car trucks having upper and lower end extensions the inner faces of which are provided with cylindrical concave seats having a common axis extending lengthwise of said side frame.
13. A side frame for car trucks having an enlarged, cylindrical, central bearing opening and integral upper and lower end extensions, the inner faces of which are provided with concave seats.
14. A journal box of the Master Car Builders' type provided with upper and lower cylindrical bearing surfaces having a common axis at right angles to the axis of the box.
15. A journal box of the Master Car Builders' type provided with an upper, unobstructed cylindrical bearing surface, the axis of which is substantially in the same plane with and at right angles to the axis of the box.
16. In a car truck, a journal box of the Master Car Builders' type having a convexly rounded, upper, bearing surface

struck from a center substantially in the same plane with the axis of the box, a side frame having a part extending over said box and provided with a correspondingly shaped, concave seat for said bearing surface; and means for holding said box in position arranged to permit the transverse rocking movement thereof about an axis at right angles to and substantially in the same plane with the axis of the box.

17. In a car truck, a journal box having an upper, convex, cylindrical bearing surface, the axis of which is transverse to and

substantially in the same plane with the axis of the box, said side frame extension 15 having a correspondingly shaped, concave seat for said bearing surface, and detachable means for removably securing said box in position arranged to permit the transverse rocking movement of said box about 20 such transverse axis.
